ELECTRICALLY OPERATED TIME SWITCH CLOCK

Donald Rose, Dayton, Ohio, assignor to Water Refining Company, Inc., Middletown, Ohio, a corporation of Ohio

Filed Mar. 26, 1962, Ser. No. 182,329

10 Claims. (Cl. 200—38)

This invention relates to an improved electrically operated timer and its actuation of switches.

An object of the invention is to provide a first electric clock motor to solely drive an hour hand which triggers as desired the actuation of a second drive motor to periodically drive a cam disc operator for operating switches.

Another object is to provide for a periodically driven cam disc which controls the operation of time switches and to provide ease of setting the time for operation of the cam disc.

A further object of the invention is to provide in the cam disc circular cam areas for operation of switches with such areas having adjustable length slots therein for the switch actuation.

A still further object of the invention is to provide for manual push button actuation of the cam disc for selectively setting into operation the drive of the cam disc by an electric motor.

Yet a further object of the invention is to provide adjustable positionable cam slot sector pieces for a cam disc to easily vary the slot length thereof for switch actuation by such slots for desired periods of rotation of the cam disc.

These together with other objects and advantages which become subsequently apparent reside in the details of construction and operation as more fully hereinafter described and claimed, reference being had to the accompanying drawings forming a part hereof, wherein like numerals refer to like parts throughout, and it which;

FIG. 1 is a front view of the electrically operated time switches showing the regeneration time set disc, the 24 hour hand therebehind and the manual operated push button;

FIG. 2 is a top plan view of FIG. 1 with the top lid removed to show the day star wheel;

FIG. 3 is an exploded view of the 24 hour hand, the day of the week star wheel dogged thereby and the 24 hour clock drive motor and gearing;

FIG. 4 is an exploded view showing the two hour cam discs for operating switches, two hour cam disc drive motor and gearing and 24 hour clock and drive gearing in phantom;

FIG. 5 is a front elevational view of the two hour cam disc with its adjustable cam slots on an enlarged scale;

FIG. 6 is a rear elevational view of the two hour cam disc of FIG. 5 showing also the drive gearing;

FIG. 7 is a top plan view of the two hour cam shown in FIG. 5;

FIG. 8 is a sectional view on line 8—8 of FIG. 5 of the adjustable cam slot on an enlarged scale;

FIG. 9 is a fragmentary top plan view on an enlarged scale of the day star wheel and its cam and two hour motor switch about to be actuated by an in down position day pin and cam slot in two hour cam;

FIG. 10 is a view similar to FIG. 9 with the day star wheel having just been dogged so that its down day pin actuates the two hour motor switch to on position and the two hour cam having rotated so its cam slot holds two hour motor switch in on position;

FIG. 11 is a sectional view of the day star wheel, a down day pin and the cam operated thereby on line 11—11 of FIG. 9;

2

FIG. 12 is a front elevational view of the cam operated by the star wheel down day pin and the two hour motor switch arm operated by a pin on the cam;

FIG. 13 is an enlarged fragmentary top plan view of the normally off micro switch for the two hour cam drive motor;

FIG. 14 is an enlarged fragmentary top plan view of a normally off two hour cam disc operated micro switch in normally off position;

FIG. 15 is a rear elevational view of the two hour cam disc and the micro switches operated thereby; and

FIG. 16 is a front plan view of the manually operated push button for operating the two hour cam disc with a portion of the front of the cam disc broken away to show the pins.

The electric timer is generally indicated at 10 and the mechanism is fully contained within a housing 11 of suitable molded plastic of generally overall square box-like shape with a circular boss 12 at the front which has a circular recess 12a therein with a reduced diameter cavity 12b extending into the housing to receive the cam disc to be described and a circular dial-like face 13 having twenty four hour day indicia markings 13a in contrasting colors for a.m. and p.m. The face 13 has a transparent portion so that a portion of an hour hand 24 therebehind may be seen. The face 13 seats on a shoulder adjacent the outer edge of boss 12 and is easily rotatable therein by an annular center knurled outwardly protruding portion 13b. The face 13 is held in by a removable retainer 14 secured by a screw 14a which threads into the housing 11. An indicia marking 15 is engraved into the housing or otherwise applied at its upper portion in the circular boss as a reference marking for setting the face 13 for desired time of switch actuation as will be more fully discussed. The reduced diameter recess 12b extending into the housing 11 from the circular boss 12 terminates in a suitable vertical partition or wall 16, see portion in FIGURES 2 and 15, which serves as a mounting for the motors, a star wheel and a manual actuating mechanism to be described. The upper part of the housing 11 has a recess 11a which terminates at its bottom in a horizontally extending mounting shelf-like portion 17 having a day of the week indicia marking 17a thereon. A suitable easily removal lid 18 closes the top recess 11a. A suitable moulded recess 19, see FIGURES 13, 14 and 15, extends into the back of the housing below the horizontal shelf 17 to receive the micro switches and their terminal connections, to be described. A removable back plate 20 is secured by screws 20a to the track of housing 11.

A centrally disposed drive shaft assembly for driving a twenty four hour hand and rotatably mounting a two hour cam disc, both to be described, is indicated at 21. This shaft assembly is mounted at its rear journal end 21a, see FIG. 4, in a suitable bearing bushing (not shown) extending through and carried by the partition 16. This shaft assembly 21 has an enlarged journal portion 21b having a peripheral recess 21c therein to receive a conventional snap over C-shaped retainer disc (not shown) and a forward journal portion 21d with an internally threaded recessed end 21e to receive a retaining screw 22. The rear journal end 21a is likewise provided with a recessed threaded end 21f to receive a suitable retaining screw whose head will provide a stop against the bearing bushing 21 (not shown) to hold the shaft assembly mounted in the partition 16.

The shaft assembly 21 is driven by a twenty four hour clock motor 22 having a gear box 22a with apertured mounting ears 22b which receive mounting screws to secure the motor clock motor within the rear of housing 11 and to partition 16. A drive shaft 22c powered by the gear box 22a extends through an aperture in partition 16

positioned to the right of shaft assembly 21 as viewed from the front. Mounted on the end of shaft 22c is a drive pinion 23 which meshes with a larger gear 24c secured to shaft assembly 21 whereby it is rotated in a clockwise direction once each 24 hour period. A twenty-four hour hand 24 has a central apertured knurled mounting hub portion 24a which is received on the journaled forward end 21d and held thereon by the securing screw 22 and an internal friction coiled spring (not shown) within the hub whereby the hand 24 may be manually adjustably rotated in the clockwise direction to set the same. The hand 24 has a transversely and rearwardly projecting lug portion 24b which rotates one step, once each day, a star wheel 25. The star wheel 25 is received on a vertically extending post 26 projecting up from partition 16 and the horizontal floor 17 of the housing, see FIG. 2, and held thereon by a C-shaped spring disc retainer 26a. The star wheel 25 is shown with seven radially projecting spaced apart fingers 25a which are bifurcated and apertured vertically to receive settable down and up pins 25b. One finger is provided for each day of the week or six fingers could be provided and an every other day setting could be utilized. The lug portion 24b on hand 24 rotates once each twenty four hours and strikes one of the fingers 25a of the star wheel to rotate the star wheel one step. A leaf spring 27 is secured to a wall of upper recess 11a of the housing by a screw 27a and its end 27b is bent at a right angle so as to springly engage between the fingers 25a and hold the star wheel in a set position when not being dogged. The purpose of the star wheel 25 and its selected down projecting pins 25b will be described.

Mounted on the horizontal floor 17 of the housing 11 is a first cam assembly 28 on a vertical pivot post 28a, see FIGURES 9, 10 and 12, received in vertical aligned apertures in floor 17 and floor 19a of recess 19 shown in FIG. 15. This cam assembly 28, as best shown in FIGURES 9, 10 and 12, is a molded unit having a triangular body 28b, a horizontally projecting finger 28c with a hooked portion 28c' extending under the fingers 25a so as to be engaged and rotated by a down pin 25b as it rotates in a clockwise direction as viewed from the top. Projecting vertically downward from body portion 28b is a pin 28d which serves to swing clockwise an actuating finger of a first micro switch, to be described, when the cam 28 is rotated by one of the down pins 25b as shown. The star wheel 25 and its actuation of first cam assembly 28 holds switch 29 closed for about thirty minutes while it is only necessary for about two minutes as the cam disc control will hold the switch 29 closed for about 350 degrees of rotation as will be explained.

The first micro switch 29 is a normally off switch and closes when in on position and completes an energizing circuit to a two hour cam drive clock motor 30. The switch 29 is of conventional construction and is shown in FIG. 13. It has an insulated mounting and terminal strip 29a to which is riveted an L-shaped mounting bracket 29b having in the outwardly projecting portion an elongated aperture 29c therethrough adjacent its outer end and extending parallel to the mounting strip 29a and an elongated recess 29d in the inner face thereof intermediate the aperture and mounting strip and parallel to the mounting strip 29a. Received over the projecting portion of bracket 29b is a specially formed conductor leaf spring member 29e of elongated annular shape with a central tongue portion 29f bent in arc shape and integral with a contact end 29g carrying contact button 29h. The free end of arcuately bent outwardly finger 29f is received in the recess 29d of the bracket. An actuating finger 29i is specially shaped at its mounting end. It has an offset portion 29j received in slot 29c in a pivotal manner and an inner end 29k bent to extend generally parallel to its main portion and received in the adjacent end of annular conductive spring member 29e. The actuating end of actuating finger 29i is indicated at 29l. The other terminal of switch 29 is a generally Z-shaped bracket 29m

which riveted to the mounting strip 29a adjacent the end movable contact 29g. Terminal L-shaped members 29n and 29p are respectively secured by the rivets to the mounting strip 29a opposite the brackets 29b and 29m to which they are electrically connected by the respective securing rivets. In FIG. 13, switch 29 is shown in normally off position but when the actuating end of finger 29i is swung clockwise initially by the pin 28d on cam assembly 28, the contact spring 29e shifts to contact the terminal 29m with which it completes a circuit to the two hour cam motor 30 to energize the same. A two hour cam disc 31 which is driven by the motor 30 will hold the outer end 29l of actuating finger 29i in the clockwise urged attitude whereupon the switch 29 is held closed to cause rotation of the cam disc as will be described.

The two hour cam drive motor 30 is of like construction to motor 22 and has a gear box 30a, mounting ears 30b by which the motor is mounted in the rear of housing 11 to the partition 16 and its drive shaft 30c projects through an aperture in partition 16 positioned to the left of the central shaft assembly 21 as viewed from the front of the timer. A drive pinion 30d is fixed to the outer end of drive shaft 30c.

The two hour cam disc 31 is built up about and held clamped together by a central hub 32 which is received over the enlarged centrally disposed journal portion 21b for free rotation thereon within the cavity 12b in housing 11 so that it positions the cam disc 31 in closely spaced relationship forward of the front face of partition 16. A C-shaped spring retainer disc (not shown) is received in the peripheral recess 21c on the shaft assembly adjacent the front end of the hub 32 to hold the cam disc in position on shaft assembly 21. Starting from the rear of the cam disc 31, as shown in FIG. 7, there is mounted on hub 32, a drive gear 33, an annular rear spacer 34, a main body 35 having an integral front annular boss 35a, adjustable cam slot section pieces 36 and 37, a disc 38 with external teeth 38a on one half the outer circular portion thereof. When the cam disc 31 is in position on the shaft assembly 21, the drive gear 33 thereof will mesh with the drive pinion 30d, see FIGURES 4 and 6, of the two hour clock drive motor 30.

The main body 35 of the two hour cam disc 31 has three cam areas therein which starting from the outside are at 41, 42 and 43.

Cam area 41 which is on the outer portion includes a sector slot 41s extending from 41a to 41b where wall portions of the slot in main body 35 extend generally radially to define the ends of the slot of cam area 41. Also in cam area 41 is the corresponding peripheral back face 41c of the main body disc 35 extending from 41b, see FIG. 6, clockwise to 41a. A guard for the bottom of slot 41 is indicated at 41d and is made up of a transversely and forwardly projecting piece 41d' and a diagonal piece 41d'' joining the outer end of 41d' and the portion indicated at 41b. This cam area 41 made up of slot 41s between 41a and 41b and the back face portion 41c cooperates with the end portion 29l of the actuating finger 29i of the first switch 29. This switch 29 is first actuated to closed position, as above described, by pin 28d on cam 28 moving the finger 29i, see FIG. 9, whereupon the two hour cam motor 30 is energized and the cam 35 and its main body 31 is rotated counter clockwise, see FIG. 10, and the end 29l of the cam finger 29i rides on the back surface cam portion 41c to hold the switch contact 29g closed against contact 29m, see FIG. 13. Upon completion of one rotation of cam 35, in say a two hour period, the finger 29i drops into a slot 41s between 41a and 41b of cam area 41 and the finger swings counter clockwise to open the switch contacts and breaks the energizing circuit to motor 30.

The second cam area 42 on cam disc 31, more specifically on the main body 35 of the cam disc will now be described. This comprises in main body 31, see FIG-

URES 5 and 6, an arcuate slot 42s extending from radially extending shoulder 42a to adjustable cam slot sector piece 36 at 36b thereon. The rest of cam area 42 in the arcuate back surface area 42c in arcuate alignment with the slot 42s.

The third cam area 43 on cam disc 31, more specifically on the main body 35 of the cam disc is now described. Reference to FIGURES 5 and 6 shows that this comprises in the main body 31 an arcuate slot 43s extending from 43a to the 37b on adjustable cam slot sector piece 37 and a back surface area 43c in arcuate alignment with the slot 43s. In use the ends of the actuating fingers 44i and 45i of micro switches, such as shown in FIGURE 14 at 44 and 45, ride on their respective cam areas 42 and 43 and upon dropping into slots 42s and 43s such fingers swing and close their switch contacts to complete circuits as desired. When the end of the actuating finger rides on the back face cam area 42c and 43c respectively, the fingers 44i and 45i are swung to hold their switch contacts open. In FIG. 15 the actuating fingers 44i and 45i of these micro switches 44 and 45 are shown projecting in suitable slots 19s in wall 16 adjacent the recess 19 in the housing 11.

Each of the lengths of slots 42s and 43s may be adjusted by use of the respective adjustable cam slot sector pieces 36 and 37. In the main body 35 of the cam disc 31 there is formed an arcuate guide groove 46 of equal radial distance from the center of the disc shaped main body 35. The sector pieces 36 and 37 are generally alike. Sector piece 37 has a pie-like shaped main body 37c, see the broken line outline in FIGURES 5, 6 and 8, and has an inner arcuate edge 37d which rides against the outside of circular boss 35a on main body 35 while the outer arcuate edge terminates at 37e spaced in from the outer peripheral edge of main body 35. Extending transversely and integrally with the main body 37c from one edge of the sector is an arcuate boss 37f which rides in guide groove 46 in main body 35. A stop lug 37g projects transversely from the main body 37c of sector piece 37 adjacent but radially inward from the lug 37f and this stop 37g rides in the adjacent arcuate cam slot portion 43s and strikes against the adjacent end of slot 43s to limit the travel of the sector piece 37 in one direction. The travel of the sector piece 37 in its opposite direction is limited by a pin 47 against which the edge 37h of the sector piece will strike. One means of moving the sector piece 37 to an adjusted position to change the length of slot 43s is a knurled gear 48 which is pivotally mounted adjacent toothed disc 38 on a pivot post 48a projecting from sector piece 37 and secured thereon by a C-shaped spring washer. The teeth or knurling 48b of gear 48 mesh with the external teeth on disc 38. By rotating the gear 48 by ones fingers, the sector plate 37 is adjustably positioned. A suitable indicia scale 49 is provided on the front adjacent face of member 35 and a reference arrow 50 is provided on the sector piece 37. The markings here shown are in minutes and they are here labeled as for Backwash when the timer is used with an automatic water softener.

The adjustable cam slot sector piece 36 is of like construction but its transverse integral stop rides in cam slot 42s and is positioned radially outward of the lug 36f of piece 36 which rides in guide groove 46. A stop pin 47a is provided to limit the travel of sector piece 36 in one direction of travel.

The adjustable cam slot sector piece 36 cooperates with cam slot 42s to adjust its length. The cam actuating area 42 is used to control the actuating finger 44i of micro switch 44. Suitable indicia and minute markings are here shown as for a Fast Rinse of an automatic water softener. The micro switches 44 and 45 each control a solenoid which operates a respective valve mechanism in an automatic water softener. However, the timer may be used for other control systems. It will be noted that micro switch 44 and its like switch 45 whose actuating

finger 45i shown in FIGURE 15 has contacts arranged somewhat the reverse of switch 29. In switch 29 when the actuating lever is swung clockwise, the contacts make its complete circuit. In switch 44, here illustrated, swinging of the actuating lever 44i clockwise breaks the contacts to off and when swung counter clockwise the contacts are on.

A manual push button operator for initially rotating cam disc 31 is shown in FIG. 16. The initial rotation of the cam disc 31 is just sufficient to rotate it so its slot 41s permits the end 29i of actuating finger 29i to swing so as to close the contacts of switch 29 and energize the power circuit to the two hour cam motor 22 to rotate cam disc 31 for the balance of one rotation whereby the actuating fingers of switches 44 and 45 are made to operate their respective switches in proper selected relation. For example, when the timer is used with an automatic water softener one push on push button 55 will move the cam disc 31 to make the cam disc run through a complete rotation, i.e., a complete cycle of the water softener.

Two pushes on the button 55 will rotate the cam disc 31 a sufficient amount to initiate, for example, a short backwash and a full brine and fast rinse in an automatic water softener to which the timer is connected. In other words, the initial part of a full cycle is passed over all at once.

Three pushes on the button 55 will rotate the cam disc 31 so as to position the cam disc 31 for a short brine and a fast rinse wherein a prior part of the complete cycle is passed over all at once.

The push button 55 and how it imparts stepped limited rotation to cam disc 31 will now be described. The push button 55 is mounted in the housing 11 so as to protrude to the outside left as viewed from the front of the timer thereof. The button 55 is reciprocably mounted in the housing 11 and has a plate member 55a with an elongated slot 55b therein. Plate portion 55a rides adjacent and parallel to the front face of partition 16 adjacent the lower portion of the housing and the slot 55b thereof receives a pin 56 projecting out from the front face of wall 16. The push button 55 is held biased in out position by a tension spring 57 anchored at one end to the housing partition 16 by a screw 57a and at its other end it connects with the plate 55a of the push button.

Three pins 58, 59, and 60 arcuately spaced apart and equally distant from the center of main body 35 project from the adjacent rear face of the main body 35. These pins are so positioned that pin 58 is adjacent plate 55a when the cam disc 31 is at position of rest, i.e., switch 29 is open. A flat spring pusher member 55c is attached to the plate 55a of the push button and is shaped at its unattached end with a right angle offset portion 55d to engage pin 58. Thus, when the push button is pushed in once, as stated above, the cam disc 31 is rotated counter clockwise an arcuate amount as indicated by the broken line position of plate 55a and pin 58. This action, as stated above to initiate a complete cycle, moves actuating arm 29i of micro switch 29 out of slot 41s and the switch contacts close to complete an energizing circuit to motor 30 to drive cam disc 31 the balance of one complete turn whereupon the end 29i of actuating arm 29i drops into slot 41s and opens the contacts of switch 29 to stop motor 30. The push button when pushed two times will catch pin 59 on the second push as pin 59 has moved to take up the prior position of pin 58 adjacent pusher 55d on the first push and, as explained above, a short backwash and full brine and fast rinse cycle is initiated. On the third push on button 55, pin 60 is in line with pusher 55d and it is pushed to rotate the cam disc 31 so as to carry out a short brine and fast rinse cycle, as explained above.

While not shown, flexible terminal connectors for the terminals of switches 29, 44 and 45 and the motors 22 and 30 are easily lead to terminal connectors (not shown) on the removable back 20 of the housing 11. In the use of the timer, electrical power connections may be lead to

the terminals leading to the motor 30 to initiate drive of the cam disc 31 from a remote position such as from an over flow indicator of a water softener brine tank. In the setting of the timer, the particular days of actuation are selected by pushing down the desired day buttons 25b on star wheel day of the week as marked on the lug 25a carrying the button is positioned adjacent the Day arrow 17a on shelf 17 of the housing 11. The time of day desired for actuation of the two hour cam disc 31 is set by just rotating the face or disc 13 to bring the hour desired adjacent the arrow 15 on the housing. After this the twenty-four hour hand 24 is set for the time of day by rotating same as it appears behind a transparent circular part of the face 13.

As can be seen there is provided in this timer a very small load on the twenty-four hour clock motor 22 and its gear train to rotate hand 24 once each twenty-four hours to in turn rotate the star wheel 25 one step per twenty-four hour day. Star wheel 25 turns with little resistance and therefore on the continuously running motor 22 there is little load. By this means very accurate time and proficient performance is realized. The periodically energized two hour, for example, cam motor 30 is the motor which carries the most load. The cam disc 31 operates the micro switches such as 44 and 45 and while there is not a great amount of load on the motor 30, there is more than on motor 22. The accuracy required here with the drive of cam disc 31 is not so great as with the twenty-four hour timer.

While two switches 44 and 45 have been illustrated, it would be possible to enlarge the timer to accommodate additional cam areas like areas 42 and 43 on the cam disc 31 to accommodate respectively more switches for use with various circuits.

A highly advantageous feature of this timer is the ease and accuracy of adjusting the length of cam slots 42s and 43s by means of the respective adjustable cam slot sector pieces 36 and 37. The gear drive adjustment of these sector pieces makes for ease and accuracy of positioning of the same. While gear drive movement of the sector pieces 36 and 37 is illustrated other adjusting means may be used.

I claim as my invention:

1. An electric timer for opening and closing switches, comprising, in combination, a housing having mounted therein, a first and at least a second switch, each of said switches having a pivotal actuating finger, a first motor for driving continuously a hand making one revolution every twenty four hours, a second motor for driving periodically a period cam disc, a period cam disc driven by said second motor, a day of the week star wheel having individual day positionable pins therein, a twenty four hour hand driven by said first motor and having a portion thereon positioned for rotating said star wheel in one day advance position per each twenty four hours rotation, pivotal cam means adjacent said star wheel and pivoted by a positioned pin of said star wheel, said cam means having an arm thereon for engaging the actuating finger of said first switch positioned thereadjacent to close and open the same, said first switch when closed being connected to energize said second motor, said period cam disc having a first slot therein within which the end of said first switch finger positioned thereadjacent rests in open position of its switch when not actuated by said arm on the pivotal cam means therefor and at least a second slot in said cam disc positioned in radial distance from the first slot for receiving the actuating finger of said second switch positioned thereadjacent for actuation to one position, said fingers of said switches riding on the respective adjacent portions in said cam disc to said slots when not resting in said slots whereby said switches are actuated to an opposite position, said first switch being held closed after said initial closure by said first switch finger riding on said disc portion for

energizing said second motor whereupon to rotate said period cam disc one revolution.

2. An electric timer for opening and closing switches according to claim 1 including a twenty four hour annular disc mounted in said housing adjacent said twenty four hour hand and manually rotatable in said housing for setting.

3. An electric timer for opening and closing switches according to claim 1 wherein said twenty four hour hand 10 is mounted for drive by said twenty-four hour motor and for manual setting and including a twenty four hour annular disc mounted in said housing adjacent said twenty four hour hand and manually rotatable in said housing for setting.

4. An electric timer for opening and closing switches according to claim 1 including a manually positionable actuating member mounted in said housing adjacent said period cam and actuatable from outside the housing for initiating rotation of said period cam disc, said period cam disc having spaced apart pins arranged arcuately thereon for sequential engagement by said manual actuating member whereupon said period cam disc is rotated a selected amount and said first switch actuating finger is actuated to close said first switch whereupon said second motor, is energized to drive said period cam disc and said cam disc is driven thereby for the balance of a rotation to actuate said second switch.

5. An electric timer according to claim 1 wherein said period cam disc has means movably attached thereto and 30 with a portion thereof slidable at one end of said second slot for adjusting the effective length of the slot within which said second switch actuating finger extends.

6. An electric timer for opening and closing switches, comprising, in combination, a support means having 35 mounted therein, a first and at least a second switch, each of said switches having actuating means attached thereto, a first electric motor for driving continuously a hand making one revolution every twenty four hours, a second electric motor for driving periodically a period cam disc, a period cam disc driven by said second motor, a star wheel having individual day positionable pins therein, a twenty four hour hand driven by said first motor and having a portion thereon positioned for rotating said star wheel in one day advance position per each twenty four 45 hours rotation, pivotal cam means adjacent said star wheel and pivoted by a positioned pin of said star wheel, said cam means having an arm thereon for engaging the actuating means of said first switch positioned thereadjacent to move it to close said first switch, said first switch when closed being connected to energize said second motor, said period cam disc having a first slot therein within which said first switch actuating means positioned thereadjacent rests in open position of its switch when not actuated by said arm on the pivotal cam means therefor and at least a second slot in said period cam disc positioned in spaced 50 radial distance from the first slot for receiving the actuating means of said second switch positioned thereadjacent for actuation to one position, said means for actuating said switches riding on the respective adjacent portions in said cam disc to said slots when not resting in said slots whereby said switches are actuated to an opposite position, said first switch being held closed after said initial closure for 55 energizing said second motor by said first switch actuating means riding on said cam disc portion whereby said second motor rotates said period cam disc one revolution.

7. An electric timer according to claim 6 wherein said period cam disc has means movably attached thereto and with a portion thereof slidable at one end of said second slot for adjusting the effective length of the slot within 60 which said actuating means extends for actuating the second switch.

8. In an electric timer having a motor driven period cam disc for cooperation with actuating arms of electrical switches, a period cam disc comprising a main disc portion having an axis therethrough, a drive gear attached

to one face of said main disc with its axis in alignment with that of the main disc, a series of concentrically arranged arcuate cam slots in said main disc disposed at varying radial distances from the center of said main disc, a central circular hub extending transversely from the other face of said main disc, a positionable cam slot sector piece mounted for movement on said other face of said main disc and having an inner arcuate portion slidably abutting against an adjacent peripheral circular portion of said hub and a transversely extending portion thereon slidably received in one of said arcuate cam slots, said sector piece having means thereon for holding the same adjustably positioned on said main disc whereby the effective length of the slot with which it cooperates may be varied.

9. A period cam disc for an electric timer according to claim 8 including a disc attached to said hub and having a portion thereof overlying a portion of the adjacent sector piece and having a toothed exterior arcuate portion thereon adjacent said sector piece and wherein said means for positioning and holding the sector piece in adjusted position with respect to the main disc and its

slot includes a knurled gear member pivotally mounted on said sector piece adjacent toothed sector portion on said disc adjacent said hub and having a portion of the knurled portion of the gear meshing with said tooth portion whereby by turning the gear adjusts the arcuate positioning of said sector piece with respect to the main disc and the cooperating slot for the sector piece.

10. A period cam disc for an electric timer according to claim 9 wherein said main disc has an arcuate groove in said opposite face thereof concentric with said slots therein and said sector piece overlies a portion of said groove and has a transversely extending arcuate lug thereon slidably received within said adjacent groove in the main disc.
